ACCORDION

Richard R. Rieschick, New York, N. Y.

Application June 10, 1947, Serial No. 753,683

6 Claims. (Cl. 84—376)

1

This invention relates to accordions.

The invention has for its object to provide a structure which may be made largely of plastic material, preferably transparent, and of such structural features, whereby the parts may be made under mass production, and readily assembled, in order to remove as much of the usual handwork as possible, and thus reduce the cost of production; and extend the general use of such accordions.

For this purpose the invention consists of a bellows part which has at each of its open ends a frame with flanges. Two end parts are provided each of which fits against said flanges of the bellows part. Each end part has a transparent membrane supporting reed casings on one side, and having openings in registration with the reed casings, and having novel valves on its other side, governed by actions, operated by keys or button levers.

The keyboard and the button board are separate permitting the main parts to be used for different keyboards or different bass button boards.

The keys are of novel shape having a metallic rib integral with the action and a plastic covering, the covering having flanges movable in spaces formed by a plurality of guide ribs.

The invention will be more fully described, an embodiment thereof shown in the drawings, and the invention will be finally pointed out in the claims.

In the accompanying drawings,

Fig. 1 is a perspective view of the improved accordion;

Fig. 2 is a right hand end view;

Fig. 3 is a section taken on line 3—3 of Fig. 2;

Fig. 4 is a vertical transverse section with the parts spaced from each other;

Fig. 5 is a vertical transverse section taken on line 5—5 of Fig. 1;

Fig. 6 is a transverse section taken on line 6—6 of Fig. 5;

Fig. 7 is a transverse section taken on line 7—7 of Fig. 5;

Fig. 8 is a vertical transverse section taken on line 8—8 of Fig. 1;

Fig. 9 is a plan view of the valve operated by the key depressed lever;

Fig. 10 is an enlarged longitudinal section taken on line 10—10 of Fig. 9;

Fig. 11 is an enlarged transverse section taken on line 11—11 of Fig. 10;

Fig. 12 is a perspective view of a white key;

Fig. 13 is a bottom view of the upper unit taken from line 13—13 of Fig. 5;

2

Fig. 14 is a bottom view of Fig. 5, and Fig. 15 is a broken section taken on line 15—15 of Fig. 14.

Similar characters of reference indicate corresponding parts throughout the various views.

Referring to the drawings, the improved accordion consists essentially of three parts, A, B and C.

The part A (see Fig. 4) consists of an upper frame 15 of suitable plastic material, having upwardly extending flanges 16 and 17, a lower frame 15a of suitable plastic material having downwardly extending flanges 16a and 17a, and a bellows 20, having its open ends secured by suitable fastening to each of the inner sides of the frames 15 and 15a. The parallel flanges 16 and 17 as also the parallel flanges 16a and 17a form outwardly open channels 18 and 18a. The inner flanges 17 and 17a are slightly lower than the outward flanges 16 and 16a. The part A is of general rectangular shape with rounded corners, determining the general shape of the accordion.

The upper part B (see Figs. 4 and 5) consists of a body portion 21 open at its lower end of a suitable height, extending circumferentially and of a shape of general rectangular character with rounded corner portions, conforming to the shape of the part A. Within this body portion 21, and at its upper end, there is provided a membrane 22

of suitable plastic material, preferably transparent, which has peripheral flanges 23, the size of this flanged membrane being such as to fit within the body portion 21 to abut against shoulder 24 and 24a of the body portion 21, with the

outer surfaces of the flanges 23 closely hugging the inner surface of the body portion 21, and preferably held by acetone. To the lower side of the membrane 22, a plurality of casings 25 are secured, which have the reeds 26 and felts

27 (Fig. 4), and which communicate with openings 28 in the membrane 22. These reeds and felts are well known and are not described in detail, attention being called to the simplicity of the casings 25, also made of suitable light weight

material. Thus, the membrane 22 supports the casings 25, and the removal of the membrane 22 from the body portion or casing 21, removes the casings 25, and vice versa the insertion of the membrane 22 inserts the casings 25. The upper part of the body portion 21 curves over to the wall 24b. A cover 30 of grill form is suitably attached by screws or rivets 31 to the wall 24b. The cover 30 has in the embodiment shown in Fig. 1, a plurality of openings 30a (Fig. 1). The rear ends of the wall 24b and the cover 30 terminate short of the rear of the body portion 21. Above

the shoulder 24a, the body portion 21 extends upwardly as shown by the extension 32 having an inclined surface 33. There is a space between the rear of the cover 30 and the extension 32 and through this a detachable keyboard 35 is inserted, and when inserted it is secured to the body portion 22 by screwbolts 36, having nuts 37 (Fig. 5). The removability of the nuts 37, and bolts 36, enables the keyboard 35 to be removed, and a different one replaced therein. Thus, means are provided for an interchangeable keyboard. The keyboard 35 consists of a back plate 38 having marginal flanges 39 and 39a, which flanges 39 and 39a are parallel with each other, and support a pivot rod 39b for the white and black keys 40, 40a, (Figs. 1 and 5). The back plate 38 has an inwardly extending flange 41, the outer surface of which is provided with a felt layer 42 (Fig. 5).

The keys 40 are made of a suitable plastic material and are of special construction, as shown in Figs. 6, 7, 8 and 12. Each key 40 consists of a flat outer surface 42 to be pressed by the fingers, with outer parallel flanges 43, and a pair of parallel flanges 44, spaced from each other to allow for the entrance of one end of a metal strengthening bar 45, which extends forward to form an extension 45a to rest below the flange 41, and to act as a stop device, when the key 40 and consequently the bar 45 is relieved of finger pressure. A spring 46 has one end 47 press against the bottom of the bar 45. This end 47 is bent to enter a hole in the bottom of the bar 45. The spring 46 is then coiled one turn to form a coil 49, and its other free end 50 presses against the back plate 38. The white key operation is shown in Fig. 5, and the black key operation is shown in Fig. 8. The back plate 38 has an abutment 51, with a felt covering 52 to serve the same purpose for the black keys 40a as the flange 41 and its felt covering 42 serves for the white keys, namely, to dampen the shock, when the keys are pressed of the pressure of the fingers. The spring 46 for the black keys is shorter than the spring 46 for the white keys. The spring cannot fall out of its nest accidentally.

The back plate 38 has a plurality of parallel guide ribs 38a forming spaces for the movement of the keys, as shown for the black keys 40a in Fig. 7. The flanges 43 and 44 of the white keys 40 (Fig. 6) do not enter the spaces between the guide ribs 38a, as blue guide ribs 38a terminate about where the reference character 47 appears in Fig. 5.

Each white key 40 and each black key 40a is pivoted on the rod 39b, and each has an action member 55, to the free end of which a valve 56 is secured as shown in Figs. 5, 9, 10, 11 and 12. The member 55 is integral with the bar 45.

The end of each action member 55 has a curved recess 57 (Figs. 9 to 12) engaging a curved abutment 58 of a separate frame 59 of the valve 56. The lower surface of the member 55 is provided with a leather layer 60 of U-shape, which slidingly engages a leather layer 61, secured to a rigid member 62, having at its lower side, a leather layer 63 (Fig. 10). The curved recess 57 and curved abutment 58, and slideable connection, gives substantially a universal motion connection. By pressing any key, black or white, the corresponding action 55, there being one for every key, is actuated. The valve 56 is then raised from the membrane 22, whereby the casing 25 is opened to the atmosphere, and the air compressed by the reeds, with the sound passing out of the openings 28, and through the open spaces 75

30a of the cover 30 to the atmosphere. The connection enables the valve 56 to close all parts of its opening.

When this cover 30 is removed, the keyboard 35, with all the keys and actions, may be removed, and another substituted, the bolts 36 and nuts 37 being, of course, removed and replaced. The keyboard 35 has lateral extension 35a with curved finger recesses 35b (Figs. 1 and 2), which extensions enable the accordion to be readily grasped.

The part A and the part B are joined by inserting the body portion 21 of part B into the space between the flanges of part A, and then fastening the parts together by screws 64 (Fig. 5). A similar connection is provided in order to join part A to part C (Fig. 5), where the flanges 16a and 17a hold by means of screws 64a, the marginal wall 65 of the part C. Thereby a basic housing is provided.

Generally considered, part C is the reverse of part B. In part C, the body portion 70 has the before referred to marginal wall 65, which extends beyond a shoulder 71, upon which a membrane 75 is seated (Fig. 5). This membrane 75 is a suitable transparent or translucent plastic material like the membrane 22, and on its outer or upper sides has connected thereon reed casings 76, the membrane 75 having corresponding openings 77, opened or closed by valves 78, preferably of the construction shown in Fig. 10, each connected with an action lever 79, pivoted on the shaft 80, and having an elbow lever 81 engaged by an actuating rod 82 having a button 83. The buttons 83 each pass through an opening in a button board 84, as known. A spring 85 presses the lever 81, to hold the valve 78 closed, the pressure on the button opening in the same. The shaft 80 is supported on a plastic material frame 80a, secured to the membrane 75 (Fig. 5) on the other side to that of the reed side.

The membrane 75, is secured to the shoulder 71, by screws 74 (Fig. 5). These screws can be omitted and the fastening can be carried out by other means as a cementing as by acetone, in the manner described in connection with membrane 22. Thus, the body portion 70 forming essentially the part C and forming a closure or casing, may with the membrane 75, be separated from part A, by the removal of the screws 64a, and the membrane 75 may be separated from the body portion 70, by the removal of the screws 74. The membrane 75, like the membrane 22, carries the plurality of reed casings, which extend into the space within the bellows formed by the two detachable membranes 22 and 75.

The bass plate or button board 84 may also be readily substituted by another with a different number of buttons, the valves 78 and reed casings 76 and openings being modified in number accordingly.

The body portion 70 has a rim 86 on which is seated a separable bottom plate 87. The bottom plate 87, two projections 87a which fit into recesses 102 in the wall 86 (Fig. 14), and the other end of the plate 87 are secured to the wall 86 by screws 101 or the like. A guide 88 is provided against which the bass or button plate 84 is seated against a rim 89. The other or lower end of the bass plate is held in place by the bottom plate 87 (Figs. 4 and 5).

The body portion 70 extends downwards to form integral parallel flanges 94, which serve to rest the accordion on a table.

The part C has a strap 90 with holes 90a ad-

justably secured by screws 91 to the inside of the body portion 70, the leather strap 90 passing through a gap formed by the body portion 70 and rim 86, the other end of the belt 90 having a stop 92 locking the end to the opposing rim 36 and spaced abutment 93 (Fig. 15).

A shoulder strap known and not shown, is adapted to be secured to metallic straps 95, one at each rear corner of part B (Figs. 1 to 3). The plastic wall of the body portion 21, curved at its rear corners, is provided at its inner surface with a metallic reinforcing sheet 96. Holes in the sheet 96 in the wall 21 and in a pair of bases 97 register with each other. Bolts 98 pass through these holes. Nuts 99 are provided. The straps or bars 95 extend from the base 97 of one pair to the other base of that pair, the bars 95 being spaced from the body portion a suitable distance for the passage of the shoulder straps. By placing the metallic straps 95 on the corners, the shoulder strap is kept from interfering with the bellows.

The exterior of the accordion is provided with a closure strap 20a, as known (Figs. 1 and 2).

From the foregoing it is clear that the bellows part A has at each open end of the bellows 20, a frame with outwardly extending spaced flanges each frame adapted to receive the body portion of the part B or the part C.

Each part B and C has a transparent membrane, supporting the reed casings, whereby upon the removal of the membrane which fits snugly into the body portions, the reed casings are likewise removed.

The part A has the replaceable keyboard and actions.

The part C has the replaceable button board and actions and the removable actions and valves cooperating with the membrane of part C.

The novel keys and guide ribs form an important feature of the invention.

I have described several forms of my invention, but obviously various changes may be made in the details disclosed without departing from the spirit of the invention as set out in the following claims.

I claim:

1. In an accordion, a bellows, a frame for each open end of the bellows, said frame having a marginal flange, an end member having a shoulder at its interior, and a circumferential wall, a membrane having a marginal rim seated against said shoulder, for supporting reeds, a second end member having a shoulder at its interior, and a circumferential wall, a membrane having a marginal rim seated against the shoulder of the second end member for supporting reeds, means fastening the flange of the frame of one end of the bellows to the wall of the first end member, and means fastening the flange of the frame of the other end of the bellows to the wall of the second end member, said parts forming the main structure of the accordion.

2. In an accordion, a bellows, a frame for each open end of the bellows, said frame having a marginal flange, an end member having a shoulder at its interior, and a circumferential wall, a membrane having a marginal rim seated against said shoulder, for supporting reeds, a second end member having a shoulder at its interior, and a circumferential wall, a membrane having a marginal rim seated against the shoulder of the second end member for supporting reeds, means fastening the flange of the frame of one end of the bellows to the wall of the first end member,

and means fastening the flange of the frame of the other end of the bellows to the wall of the second end member, said parts forming the main structure of the accordion, said first end member having a keyboard entrance, and a separate keyboard with key actions and valves in said entrance and secured to the first end member.

3. In an accordion, a bellows, a frame for each open end of the bellows, said frame having a marginal flange, an end member having a shoulder at its interior, and a circumferential wall, a membrane having a marginal rim seated against said shoulder, for supporting reeds, a second end member having a shoulder at its interior, and a circumferential wall, a membrane having a marginal rim seated against the shoulder of the second end member for supporting reeds, means fastening the flange of the frame of one end of the bellows to the wall of the first end member, and means fastening the flange of the frame of the other end of the bellows to the wall of the second end member, said parts forming the main structure of the accordion, said membrane in the second end member having valve actions for valves on the side opposite to the reed side, and a bass keyboard for buttons actuating said actions.

4. In an accordion, a bellows, a frame for each open end of the bellows, said frame having a marginal flange, an end member having a shoulder at its interior, and a circumferential wall, a membrane having a marginal rim seated against said shoulder, for supporting reeds, a second end member having a shoulder at its interior, and a circumferential wall, a membrane having a marginal rim seated against the shoulder of the second end member for supporting reeds, means fastening the flange of the frame of one end of the bellows to the wall of the first end member, and means fastening the flange of the frame of the other end of the bellows to the wall of the second end member, said parts forming the main structure of the accordion, said membrane in the second end member having valve actions for valves on the side opposite to the reed side, and a bass keyboard for buttons actuating said actions.

30 5. In an accordion, a bellows, a frame for each open end of the bellows, said frame having a marginal flange, an end member having a shoulder at its interior, and a circumferential wall, a membrane having a marginal rim seated against said shoulder, for supporting reeds, a second end member having a shoulder at its interior, and a circumferential wall, a membrane having a marginal rim seated against the shoulder of the second end member for supporting reeds, means fastening the flange of the frame of one end of the bellows to the wall of the first end member, and means fastening the flange of the frame of the other end of the bellows to the wall of the second end member, said parts forming the main structure of the accordion, said second member having parallel supports integral with the end member.

35 40 6. In an accordion, a bellows, a frame for each open end of the bellows, said frame having a marginal flange, an end member having a shoulder at its interior, and a circumferential wall, a membrane having a marginal rim seated against said shoulder, for supporting reeds, a second end member having a shoulder at its interior, and a circumferential wall, a membrane having a marginal rim seated against the shoulder of the second end member for supporting reeds, means fastening the flange of the frame of one end of the bellows to the wall of the first end member, and means fastening the flange of the frame of the other end of the bellows to the wall of the second end member, said parts forming the main structure of the accordion, said second member having parallel supports integral with the end member.

ports, with one side against said valves and its other side supporting reeds controlled by said valves, said membrane being slidable from said open end to and from said interior shoulder, said circumferential wall at its margin being aligned with and engaging the flanges of the frame at one end of the bellows, and said lower end part consisting of a casing having a button board, valve levers and valves, and formed of an open ended circumferential wall with an interior shoulder 10 inwardly of said open end, and a membrane on said shoulder separate from the casing and having valve ports, with one side against said last named valves and at its other side supporting reeds controlled by said valves, said membrane 15 being slidable from said open end to and from said shoulder, said circumferential wall at its margin being aligned with and engaging the flanges of the frame at the other end of the bellows, and means fastening the flanges of the 20 bellows frames to the circumferential walls of the casings, whereby on the unfastening of said means, the three parts may be separated and the membranes with their reeds removed from and replaced to their end parts.

RICHARD R. RIESCHICK.
